BOAT FENDER

Raymond L. Bryan, Newark, Del.

Application April 30, 1959, Serial No. 55,724

Term of patent 14 years

(Cl. D71—1)

FIG. 1.

FIG. 2.

FIG. 3.

Figure 1 is a front elevational view of a boat fender showing my new design, the rear thereof being the same in appearance as the front;

Figure 2 is a side elevational view thereof, the opposite side being the same in appearance, with the rope loops omitted for convenience of illustration only; and

Figure 3 is a top plan view thereof, also with the rope loop omitted, the bottom being the same in appearance.

The dominant features of my design reside in the portions shown in full lines.

I claim:

The ornamental design for a boat fender, substantially as shown and described.
